(57) **CLAIM**

The ornamental design for an electronic nasal aspirator, as shown and described.

DESCRIPTION

FIG. 1 is a front elevation view of an electronic nasal aspirator showing our new design;

FIG. 2A is a rear elevation view thereof;

FIG. 2B is an enlarged view of a portion of FIG. 2A;

FIG. 2C is an enlarged view of another portion of FIG. 2A;

FIG. 3A is a left side elevation view thereof;

FIG. 3B is an enlarged view of a portion of FIG. 3A;

FIG. 4A is a right side elevation view thereof;

FIG. 4B is an enlarged view of a portion of FIG. 4A;

FIG. 5A is a top plan view thereof;

FIG. 5B is an enlarged view of a portion of FIG. 5A;

FIG. 6A is a bottom plan view thereof;

FIG. 6B is an enlarged view of a portion of FIG. 6A;

FIG. 6C is an enlarged view of another portion of FIG. 6A;

FIG. 7A is a front elevation view of an electronic nasal aspirator with the cap removed, the sole difference being the removal of the cap;

FIG. 7B is an enlarged view of a portion of FIG. 7A;

FIG. 8A is a rear elevation view thereof;

FIG. 8B is an enlarged view of a portion of FIG. 8A;

FIG. 8C is a right side elevation view thereof;

FIG. 9B is an enlarged view of a portion of FIG. 9A;

FIG. 10A is a left side elevation view thereof;

FIG. 10B is an enlarged view of a portion of FIG. 10A;

FIG. 11A is a top plan view thereof;

FIG. 11B is an enlarged view of a portion of FIG. 11A; and,

FIG. 12 is a bottom plan view thereof.
